FIG. 1 shows a perspective view of a first embodiment of the seat in accordance with the new design.

FIG. 2 shows a front elevation view of the embodiment of FIG. 1.

FIG. 3 shows a side view of the embodiment of FIG. 1.

FIG. 4 shows a rear view of the embodiment of FIG. 1.

FIG. 5 shows a top view of the embodiment of FIG. 1.

FIG. 6 shows a perspective view of a second embodiment of the seat in accordance with the new design.

FIG. 7 shows a front elevation view of the embodiment of FIG. 6.

FIG. 8 shows a side view of the embodiment of FIG. 6.

FIG. 9 shows a rear view of the embodiment of FIG. 6.

FIG. 10 shows a top view of the embodiment of FIG. 6.

FIG. 11 shows a perspective view of a third embodiment of the seat in accordance with the new design.

FIG. 12 shows a front elevation view of the embodiment of FIG. 11.

FIG. 13 shows a side view of the embodiment of FIG. 11.

FIG. 14 shows a rear view of the embodiment of FIG. 11; and,

FIG. 15 shows a top view of the embodiment of FIG. 11. The dashed lines shown in the drawings illustrate environmental structure and form no part of the claimed design.
